UNITED STATES PATENT OFFICE.

HORACE E. TAYLOR, OF OGEMA, SASKATCHEWAN, CANADA.

ELECTRIC HAIR-SINGEING TOOL.

Application filed February 28, 1923. Serial No. 622,734.

To all whom it may concern:

Be it known that I, HORACE E. TAYLOR, a subject of the King of Great Britain, residing at Ogema, in the Province of Saskatchewan and Dominion of Canada, have invented certain new and useful Improvements in Electric Hair-Singeing Tools, of which the following is a specification.

The primary object of my said invention is the provision of an electric hair singeing tool, which is well adapted to be extensively used in barber shops and hair dressing establishments for overcoming the custom of singeing hair through the instrumentality 10 of a lighted wick or the like, which custom often times results in the undue burning of the hair, and occasionally setting fire to their garments.

A further object of my invention resides 20 in the provision of such a hair singeing tool that is comparatively simple of construction, and inexpensive of manufacture, the same embodying relatively few parts, and these so corelated, as to reduce the liability 25 of derangement to a minimum.

The nature and advantages of the invention will be better understood when the following detailed description is read in connection with the accompanying drawings, 30 the invention residing in the construction, combination, and arrangement of parts as claimed.

In the drawings forming part of this application, like numerals of reference indicate similar parts in the several views, and wherein:

Figure 1—is an elevational view of a hair singeing tool constructed in accordance with my invention.

Figure 2—is an enlarged fragmentary longitudinal cross sectional view thereof, taken substantially upon the line 2—2 of Figure 1.

Figure 3—is a view similar to Figure 2, 45 but taken upon the line 3—3 of the same figure.

Figure 4—is an enlarged cross sectional view of a specific form of plug member carried by one end of my tool handle.

Figures 5 and 6—are cross sectional views taken upon the lines 5—5 and 6—6 respectively, of Figure 1.

Figure 7—is a perspective view of a tubular insulating member employed in connection with this invention.

Figure 8—is a perspective view of a removable cap for one end of my improved tool.

Figures 9 and 10—are cross sectional views taken upon the lines 9—9 and 10—10 respectively of Figure 2.

Figure 11—is a longitudinal cross sectional view of the closure cap shown in Figure 8.

Figure 12—is a perspective view of one of the fiber strips upon which the heating wire is wound.

Figure 13—is a similar view of one of the metallic strips or arms for supporting the said fiber strip.

Figure 14—is a perspective view of a specific form of one of the spring contacts carried by a connecting socket employed in conjunction with this invention, and

Figure 15—is an enlarged end elevational view of the heating coil forming a part of my invention.

Referring to the drawings in detail, 5 designates the handle of my tool, which is preferably of wood or other non-electric material. This handle is provided with a central longitudinal bore 6, the inner end of which is enlarged for forming a socket 7 within one end of said handle 5. Within this bore 6 is one end of a relatively long 80 metallic tube 8, the inner end of which extends through a central opening in an insulating washer 9 within the inner end of said socket 7, and is flared outwardly as shown in Figure 2, for preventing the withdrawal of the tube from the handle 5. Surrounding a portion of the metallic tube 8 is a metallic tube 10, the inner end of which extends within the handle 5, and is brazed or otherwise secured to said tube 8. 95

Within the tube 8 is a longitudinally split tubular member 11 of fiber or other suitable non-insulated material, more clearly shown in Figure 7. The inner end of this fiber tube 11 is spaced from the similar end of the metallic tube 8, the opposite end thereof being reduced for forming a neck portion 12.

Within the said tubular members are a pair of spaced metallic arms or strips 13, 105 Figure 13, between which is supported a relatively elongated heating coil 14. The front end of each metallic strip 13 extends through a ferrule 15, which is positioned within an opening in the front end of the 110

said metallic tube 8, the said heating coil 14 projecting beyond the ends of said strips 13, and outwardly of the tube 8, as more clearly shown in Figures 1 and 3. The inner 5 end of each metallic strip 13 is formed with upwardly and rearwardly bent portions 16 which extend outwardly of the inner end of the metallic tube 8, and is secured within the socket 7 of said handle 5 in a manner 10 hereinafter described.

Referring to Figures 12 and 15, my heating coil 14 embodies specifically, a pair of fiber strips 17, the front end of which is formed with reduced extensions 18. The 15 heating wire of the coil 14 is extended in a longitudinal direction centrally of these strips as at 19, the same being passed through an opening 20 adjacent the front end of the top strip 17, and thence coiled in a rearward 20 direction as at 21 around both of the strips. This heating coil is as above set forth positioned between the said pair of metallic strips 13, the wire forming the coil 21 being insulated therefrom by strips of mica 22, 25 Figure 5. This coil 14 is secured between the metallic strips 13 by rivets or the like fastening means 23, it being understood that the position of these rivets is such as to be 30 out of contact with the heating wire of the coil.

Within the socket 7 of the handle 5, and in face to face contact with the insulator washer 9 therein is a fiber plug 24 consisting of rounded half sections, the front 35 end of this plug 24 being formed with a socket 25, within which are received the upwardly and rearly bent ends 16 of the said metallic strips 13, the same being secured within this socket by rivets 26. The opposite 40 ends of the heating wire of the coil 14 are respectively connected to posts 27 and 28 in the form of set screws, these wires engaging through openings 29 in each half section constituting the said plug 24. At 45 the front end of the plug 24 is a fiber washer 30 in face to face contact therewith, this disk 30 together with the plug 24 and fiber washer 9 at the front end of the plug, Figure 2, are rigidly secured 50 together by screws 31, Figures 9 and 10, the front end of these screws passing through notches 32 in the fiber washer 9 to be received within screw threaded openings 55 of the handle 5. Engaging through a central opening of the fiber disk 30 is a screw threaded end of a headed bolt 33, it being positioned upon this bolt by a pair of contact blocks 34 and 35 insulated from each other by a fiber block 36. Each of these contact 60 blocks are annularly grooved as at 37, the bolt 33 as well as the blocks being secured to the fiber disk 30 through the instrumentality of a nut 38 upon the screw threaded end of said bolt, and within a socket 39 at this end 65 of the plug 24. A conducting plate 23

electrically connects the binding post 28' with the innermost contact block 34, whilst the conducting plate 27' similarly connects the binding post 27 with the outermost block 35 through the medium of the bolt 33.

In conjunction with my tool, I employ the specific form of socket member designated in general by the numeral 38, and carried by one end of an electric terminal cable 39. Per se, this socket embodies a fiber casting 40, having a fiber plug 41 disposed therein, which plug is formed with a socket 42. Spring contact plates 43 and 44 of varying lengths are secured to one end of this plug by set screws 43' and 44', respectively, 70 which set screws also serve as the connecting medium for the separate conducting wires of the cable 39. The free ends of each of these spring contact arms are curved as at 45 for forming what may be termed 75 heads. The heads of these contact arms engage through openings 43'' and 44'' within the said plug 41, and are adapted for engagement respectively within the grooves 80 of the contact plugs 34 and 35 when the said 85 socket 38 is positioned thereon.

In Figures 8 and 11, I have shown a closure cap 45' in the form of a relatively elongated tube closed at one end and pointed as at 46, and open at its opposite end. 90 Within this tube, is a lining of felt 47, and it will at once be apparent that this closure cap is adapted for positioning over the projecting portion of the coil 15 to be received upon the metallic tube 8, and in close contact therewith for protecting this projecting portion of the coil when my tool is not being used.

In view of the above description, it is believed by me that the construction, operation and advantages of a tool of this character will be readily appreciated by those skilled in the art, and although I have herein shown and described the preferred embodiment of the present invention, it is nevertheless to be understood that minor changes may be made therein, without departing from the spirit and scope of the invention as claimed.

Having thus described my invention, 115 what I claim as new, and desire to secure by Letters-Patent is:

1. An electric hair singeing tool including a casing element having a handle portion and an elongated tube extending therefrom at one end, the handle portion being formed with a bore in line with the tube and a recessed portion at the other end of substantially larger size than the bore, and a singeing element adapted for removable mounting and housing in said casing element having a plug removably connected to said handle portion mounted in the enlarged recess therein, means carried by said plug extending through the bore in the 120 125 130

handle and the tubular casing, a heating coil carried by said last mentioned means and extending beyond the end of the tubular casing element, the plug having contact 5 with said heating coil, and an attachment plug adapted for removable connection with the first mentioned plug for connecting said heating element in an electric circuit.

2. An electric hair singeing tool including 10 a casing element having a handle portion and a tubular casing portion extending from one end thereof, said handle portion having a bore in line with the tube and an enlarged recess in the other end of the 15 handle, and a singeing element adapted for removable insertion and connection in said casing element having a fiber plug, a pair of elongated strips extending from one end of said plug through the bore in the casing 20 element, a heating element secured between said strips having a portion extending beyond the ends thereof and also beyond the ends of said casing element, contacts carried by the other end of said fiber plug having 25 electrical connection with the heating elements, and an attachment plug adapted to be removably connected to said fiber plug and engaging the contact thereon for placing the heating element in an electrical circuit. 30

3. An electric hair singeing tool including a casing element having a handle portion and a tubular casing extending from one end thereof, said handle portion having a bore in line with the tubular casing and a 35 recess in the other end thereof, and a singeing element having a fiber plug adapted for removable insertion in the recess of the handle portion, a pair of strips mounted in one end of said plug in spaced relation 40 adapted to extend through the bore of said casing element, a fiber strip member substantially longer than said pair of strips, a resistance element mounted on said strip member, the fiber strip member and resistance element extending beyond the end of the casing element and being secured between said strip within the casing element, a pair of axially aligned contacts mounted on the other end of said fiber plug and having 45 electrical connection with the resistance element, means carried by the fiber plug for removably securing said singeing element in the casing element, and an attachment plug adapted for removable connection with said 50 aligned contact on the fiber plug for inserting the resistance element in an electric circuit. 55

In testimony whereof I affix my signature.

HORACE E. TAYLOR.
